UNITED STATES PATENT OFFICE

FRANCIS W. GIBSON, OF WEST ROXBURY, MASSACHUSETTS, ASSIGNOR TO THE H. D. BEACH COMPANY, OF COSHOCOTON, OHIO, A CORPORATION OF OHIO

DISPLAY DEVICE

Application filed December 18, 1930. Serial No. 503,249.

This invention relates to display racks and particularly to a rack adapted to display and offer for sale a plurality of small articles or small packs, in each case permitting an easy and almost automatic arrangement of different articles in separate compartments in such manner that the descriptive matter and advertising borne by each package may at all times clearly be seen.

10 The several compartments, which are of general rhomboidal shape, are provided with openings permitting an easy access to the goods and are so designed that the movement of the hand in reaching for and withdrawing the goods is a practically continuous movement.

15 The general rhomboidal shape of the pockets permits a self-centering of the goods which naturally gravitate into position there-
20 in so that it is possible to fill the several compartments of the rack without the care which is usually necessary to stack packages so that the same will not be likely to fall from position. When loaded the goods are displayed
25 horizontally, that is at right angles to the eye, and the labels may be read easily.

While my rack is used to excellent advantage in the display of elongated packages such as the common packages of lift-savers and chocolate bars, it is also within the scope of my invention to produce my novel display in the form of whole counters, suitable for use in stores in such departments as sundries where it is desirable to present to view a large
30 number of articles either of similar or varied nature. Such a counter is not too high to permit the sales person to reach forward and downward to remove any selected article from its pocket, and presents an outwardly inclined surface comprising any desired number of pockets, all fully visible to the
35 purchaser.

40 In such cases, a sub-structure or other support may be substituted for the triangular support illustrated in the drawings but this will in no wise affect the general principles involved which include an inclined display area provided with a plurality of generally V-shaped bearing surfaces which when roofed become rhomboidal pockets.

Heretofore compartmented display structures have been suggested and in some cases used to more or less advantage. When, however, such compartments were open faced there was a general tendency of the goods, when the compartments were filled above the necessary retaining walls or flanges to slip off the shelf or supporting member, or a likelihood that the goods would be disturbed or accidentally displaced by customers removing packs in the case of a sale. If retaining walls held the goods in the pockets, these at the same time tended partially to hide the same and the effectiveness of the display was correspondingly lessened.

45 In the case of my display rack, it is quite impossible for the packs to escape from the compartments or to be accidentally displaced. This advantage in my stand results from the fact that the supporting surfaces of each rhomboidal pocket comprises two sloping walls uniting in a V-shaped channel. As both walls are substantially equal, any rolling or sliding tendency of the packages is a natural gravitation toward the point of the V.

50 The horizontal partitions, which in part, define the individual compartments, are slotted to permit the passage therethrough of vertical partitions, and these vertical partitions may readily be removed from the slots so that all the space between any pair of horizontal partitions may be cleaned or dusted as one unit.

55 While I have discussed and illustrated my invention especially as adapted to the display of elongated packages such as candy rolls, it will be apparent that it may be used with equally satisfactory results in a display of a great variety of articles including such hardware as screws, bolts, or nuts, or in fact almost any articles which will lie within the dimensions of the pockets. In the case of certain articles it may be desirable to provide vertical partitions at each extreme edge of the display area. This may readily be done without departing from the spirit of my invention.

60 In the drawings I have illustrated and in the specification described a form of my invention which has proven highly satisfactory

in practical use. Throughout the specification and drawings like reference numerals are employed to indicate corresponding parts.

In the drawings:

5 Fig. 1 is a perspective view of my display rack.

Fig. 2 is a plan view of one of the horizontal partitions removed.

Fig. 3 is a side elevation partly in section.

10 Fig. 4 is a fragmentary plan view of my display rack, and

Fig. 5 is a section on the line 5—5 of Fig. 3.

15 My rack comprises a base or body member 1 of generally triangular side elevation. This body portion is hollow and the interior thereof may be employed as a storage space 25 S for additional supplies of the articles to be displayed thereon. The bottom or floor panel 1¹ extends forwardly beyond the point where it meets the inclined display bearing 20 surface 1², and serves as the base 2¹ for a smaller similarly shaped body 2 which likewise to a lesser extent may also serve as a storage compartment.

25 The two inclined surfaces 1² and 2² are united to form a wide mouthed V-shaped bearing surface, the walls 1² and 2² being of equal inclination and affording a support for the goods to be displayed.

30 On the same horizontal plane as the top of the upright or vertical wall 2³ there is disposed transversely of the inclined surface 1² a horizontal partition 3 of the general construction illustrated in Fig. 2. The partition 35 3 has a rear flange 3¹ which is adapted to be riveted to the wall 1² as at 4. A front flange 3² of lesser height but disposed at generally the same angle to the partition 3 is turned upwardly to define the outermost 40 supporting surface of the partition 3. This partition 3 serves as a roof for the compartment C therebeneath.

45 This partition 3, together with that portion of the bearing surface 1² just above its point of union thereto, combine to define a second compartment C similar in all respects to that just therebeneath; and a second similar partition 3 disposed at the same angle to the inclined surface 1² provides a roof for the compartment therebelow, and with the surface 1² defines still another compartment C. Additional similar compartments C may be provided according to the size of the area 1² and the distance between the partitions 3. 55 The three storied structure illustrated has proven to be particularly satisfactory both as to size of the display stand as a whole and as to size of pocket.

50 The horizontal partitions 3 may be subdivided by any suitable number of similar vertically inclined partitions 5. The partitions 3 are slotted transversely as at 6 and the partitions 5 are slipped therethrough in interlocking relation. Each pocket thus defined by the partitions 3 and 5 is of general

rhomoidal shape and each is open-faced to permit easy loading of the compartments with the goods to be displayed and permit ready entry of the hand to remove the same therefrom.

70 In the case of such goods as candy rolls, it is possible to use the tray without partitions 5 enclosing the end compartments of each tier, and there is some advantage in such a construction as the goods may be placed in and removed from the side as well as from the front of a compartment. As stated above, such partitions may readily be provided when desired and would prevent any entry of the pocket except through the 80 front opening.

75 As shown in Figs. 1 and 3, the back wall 1³ of the member 1 extends above the inclined surface 1², and may be suitably ornamented or bear advertising matter as desired. The front panel or upright 2³ of the member 2 may be similarly used. The rear wall 1² of each pocket may also be decorated or bear matter descriptive of the content of the packs 85 to be displayed.

80 Inasmuch as the front of each horizontal partition is practically on the same plane as the back of the partition next above, the entire compartment may be filled with the 90 goods to be displayed without any possibility of the same escaping, and at the same time be clearly visible both from front and side as the glass partitions do not obstruct or prevent a ready view of the goods in adjoining compartments.

95 Inasmuch as the front of each horizontal partition is practically on the same plane as the back of the partition next above, the entire compartment may be filled with the goods to be displayed without any possibility of the same escaping, and at the same time be clearly visible both from front and side as the glass partitions do not obstruct or prevent a ready view of the goods in adjoining compartments.

100 As articles are placed in these compartments they naturally gravitate toward the point of joinder of the two inclined bearing surfaces and this gravitation continues as to all new supplies of goods added. After the V-shaped portion of the pockets is loaded, the goods may be built upward, the front inclination of the same corresponding to the slope of the member 1² and the outer edge of the glass partition 5. When all the pockets are filled to capacity, a continuous sloping field of the displayed goods is presented. Such a display is not only attractive but decidedly practical.

105 In use, the first pack to be removed of necessity will be one of the line that unites the two outer edges of the partitions 3. If the topmost pack is taken the rest of the pack will not be affected; but if a lower package be removed, the packs thereabove will simply drop down each one place. In the case of former displays of this type in which the outer layer of goods consisted of one erected on another, the removal of one would cause all above to spill out beyond the confines of the retaining flanges.

110 The rack of the particular type illustrated has found a ready use in connection with the sale of the confection known as Life Savers. These are packed twenty rolls to a 120

box, and each of the nine compartments of the rack illustrated will hold one full box. In the case of this particular candy, the three tiered rack affords a practically complete display of the several flavors in which the goods are provided. With other goods a lesser or greater number of pockets may be supplied, the number, length and spacing of the partitions being varied without departing from the spirit of my invention if within the limits of the appended claims.

What I therefore claim and desire to secure by Letters Patent is:

1. A display device comprising a floor, triangular side walls terminating inwardly of one end thereof, and a top uniting said side walls and said floor and providing a forwardly inclined surface, a second pair of triangular side walls, a front member uniting the same, and a plurality of flanged shelf members, one of said shelves being supported at its ends by the inclined edges of said second named side walls, with one of its flanges contacting said front member and its other flange overlying the lower edge of said top member and providing a surface of similar but opposite inclination to said first named display surface and uniting therewith to define a pocket for goods to be displayed.
2. A display device comprising a floor, triangular side walls terminating inwardly of one end thereof, and a top uniting said side walls and said floor and providing a forwardly inclined surface, a second pair of triangular side walls, a front member uniting the same, and a plurality of flanged shelf members, one of said shelves being supported at its ends by the inclined edges of said second named side walls, with one of its flanges contacting said front member and its other flange overlying the lower edge of said top member and providing a surface of similar but opposite inclination to said first named display surface and uniting therewith to define a pocket for goods to be displayed, and a second shelf similarly mounted on said top and providing a roof for said pocket, and with said top defining a second pocket.
3. A display device comprising a floor, triangular side walls terminating inwardly of one end thereof and a top uniting said side walls and said floor and providing a forwardly inclined surface, a second pair of triangular side walls, a front member uniting the same and a plurality of flanged shelf members, one of said shelves being supported by the inclined edges of said second named side walls and providing a surface of similar but opposite inclination to said first named display surface and uniting therewith to define a pocket for goods to be displayd, a second shelf mounted on said top and so spaced from said first shelf that its lower flange is disposed in the plane of the upper flange of said first shelf and its outer flange overlying the

channel of the pocket defined by said first shelf and said top, and providing a roof for said pocket, and with said top defining a second pocket.

In testimony whereof I affix my signature. ⁷⁰
FRANCIS W. GIBSON.
